UNITED STATES PATENT OFFICE.

ALEXANDER K. MORTON AND JOHN A. HALLORAN, OF SOUTH NORWALK, CONNECTICUT, ASSIGNEES TO THE NORWALK LOCK COMPANY, OF NORWALK, CONNECTICUT, A CORPORATION OF CONNECTICUT.

HOTEL LOCK.

Application filed April 15, 1924. Serial No. 706,683.

This invention relates to locks, more particularly locks for hotel on corridor doors, and has for an object to provide a lock which may be operated from the outside with the usual plurality of keys, but in which when locked from the inside all the keys are inoperative except the emergency key.

Another and particular object of the invention is to provide a lock which may be locked from the inside by a thumb knob or similar device, but in which turning of the inner knob controlling the latch bolt at the same time releases the lock mechanism so that the door may be opened by turning this knob only, and without requiring manipulation of any other device, thus making the lock panic proof.

It is a further object of the invention to provide a lock in which the emergency key may act as a shutout key, that is, it may be used to lock out guest and all other keys or render them inoperative, if desired.

With these and other objects in view we have devised the construction illustrated in the accompanying drawings, forming a part of this specification, it being understood that various changes in details of construction may be employed without departing from the spirit of our invention. In these drawings.

Fig. 1 is a transverse section through the lock and a portion of the door, the section being taken substantially upon line 1—1 of Fig. 2.

Fig. 2 is a side elevation of the lock mechanism with the cover plate of the lock casing removed, and showing the various elements in the positions they occupy when the door is open.

Fig. 3 is a similar view showing the elements in the positions they occupy when the door is closed, but where the guest and the regular keys have not been rendered inoperative.

Fig. 4 is a similar view showing the elements in the positions they occupy when the locking mechanism is in locking position and all keys except the emergency key are inoperative.

Fig. 5 is a view similar to Figs. 2 to 4 showing the latch bolt retarded or withdrawn from holding position by the usual knob on the inner side of the door.

Fig. 6 is a detail view of the locking lever

and associated levers looking from the opposite direction from the showing in Fig. 2.

Fig. 7 is a similar view showing the same elements in the positions corresponding to Fig. 4, and showing how the locking mechanism may be released by the emergency key.

Fig. 8 is a view similar to Fig. 6 showing the positions of the elements after the emergency key has released the locking mechanism but before the key operated cam has been brought back to a position where this key can withdraw the latch bolt.

Fig. 9 is a detail section substantially on line 9—9 of Fig. 5.

Fig. 10 is a detail section substantially on line 10—10 of Fig. 2.

Fig. 11 is a rear elevation of the key barrel showing the key operating cam.

Fig. 12 is a section of the inner end thereof substantially on line 12—12 of Fig. 11 and showing the emergency key in position, and

Fig. 13 is a similar view showing one of the pass keys or guest keys in position.

Reference numeral 15 represents a portion of the door in which the lock is mounted, and 16 represents the door casing carrying the striking plate 17 for coaction with the latch bolts. The lock mechanism is mounted in the usual casing 18 recessed within the door, and the open side of this casing is closed by the usual cover plate 19 secured in position by suitable screws in the usual manner threaded into lugs 18'. At the front the casing is closed by the front plate 20 recessed in the edge of the door and secured to the casing by suitable means, as screws 21. The front plate is also secured to the door by the usual screws 22.

Mounted in the casing is a movable latch bolt 23. This bolt is preferably mounted to slide in an opening in the front plate 20 in the usual manner, and is adapted to project into an opening 24 in the striking plate to hold the door closed, the projecting end of the bolt being beveled at 25 in the usual manner. We prefer to use a so-called antifriction latch bolt which includes a striking element 26 pivoted in the front plate at 27 and also to the bolt, as shown at 28. The free end of this element projects through the front plate in position to be struck by the striking plate when the door is closed and operates to withdraw the bolt in the usual manner without this plate striking the projecting end of the

bolt. The bolt is normally held extended by a coil spring 29 embracing the bolt and reacting at its inner end against a guide lug 30 within the casing. A plate or head 31 is carried by the bolt to coact with the means for withdrawing the bolt to be later described.

Mounted to slide transversely to the direction of movement of the latch bolt is a blocking slide 32, this slide being guided for up and down movement, as viewed in the drawing, by guide lugs 33, 34 and 35 in the casing, and has a projection 36 forming a shoulder adapted to move under certain conditions, to a position in the path of movement of a shoulder 37 carried by the latch bolt 23 to prevent retraction of the bolt, as by insertion of a tool from the outside to the latch bolt between the door and the casing. This blocking slide is controlled by an auxiliary latch 38, which is also preferably a sliding latch and projects through the front plate to a position to be engaged by the striking plate 17 when the door is closed. As the striking plate has no opening for entrance of this latch it is held in the retracted position, as shown in Figs. 3 and 4, by the striking plate when the door is closed. A coil spring 39 tends to hold this latch in extended position, the spring reacting at its inner end against the guide lug 34 which also acts as a guide for this latch. This latch also carries a head 40 which coacts with an inclined edge 41 on the blocking slide 32 to move this slide upwardly or out of the path of movement of the shoulder 37 when the door is open, as shown in Fig. 2, so that the latch bolt may be retracted. A coil spring 42 carried by a pin 43 has a free end 44 engaging the blocking slide 32, in the present instance the lug or projection 36, and tends to move the blocking slide into its lowermost or blocking position, as shown in Figs. 3 and 4, the other free end of this spring reacting against the stationary guide lug 30.

Movably mounted in the casing, as by a pivot pin 45, is a master tumbler 46 provided on its lower edge with a pair of spaced notches 47 and 48 adapted to coact with a stump or lug 49 carried by a movable shutout member of lever 50, which shutout lever has a hub 51 projecting into an opening in the casing forming a pivotal mounting for this lever, and it is held in position by suitable means, as a plate 52, secured to the casing by suitable screws 53. This shutout lever has a squared opening 54 to receive the squared shank 55 of a thumb knob or similar device 56 accessible for operation from the inner side of the door.

The tumbler 46 is also provided with an inclined edge 57 to coact with the upper edge of the head 40 on the auxiliary latch 38 when this latch is retarded by the striking plate. The action of this head is to raise the tum-

bler 46 to the position shown in Figs. 3 and 4. A spring 58 tends to move the tumbler downwardly to its lower position.

Also pivoted within the casing immediately above the tumbler, as by a pin 59, is an auxiliary controlling lever 60 which has a laterally projecting stump or lug 61 adapted to coact with the shutout lever 50 and a key operated cam as will later be described. This lever is also adapted to engage fingers 62 and 63 on a master controlling lever 64, this latter lever being pivoted on a pin 65. A spring 66 normally tends to move the free end of the lever 60 downwardly or against the finger 63. A spring 67 on the pin 65 has a free end 68 engaging a lug or pin 69 on the lever 64 and tends to move this lever clockwise, as viewed in Figs. 2 to 5. The master controlling lever 64 has a finger 70 adapted to engage the head or plate 31 on the latch bolt 23, and is located between this head and the hub lever 71 pivoted in the casing at 72, and which is adapted to be operated by a cam 73 having a squared opening 74 to receive a squared spindle 75 operable by the usual knob 76 on the inner side of the door. A spring 77 tends to move the hub lever 71 counterclockwise, as viewed in Figs. 2 to 5, and hold it against the stationary guide lug 30 and allow the latch bolt to be extended. An intermediate lever 78 is pivoted on the pin 43, one end of this lever projecting into a notch 80 in the blocking slide 32, and the other end engaging the under side of the finger 63 on the master controlling lever 64.

The shutout lever 50 is provided with a laterally projecting lug 81 adapted to be moved to and from the path of movement of the inner end 82 of an indicator button 83 to thus indicate the position of the shutout lever from the outer side of the door. The button 83 is mounted to slide in a guide 84 mounted in the outer side of the door and is normally held in its outer position by a spring 85.

The lock may be controlled by suitable keys from the outside of the door. For this purpose a key barrel 86 is secured in the door, as by threading it into the cover plate 19, and its outer end is accessible on the outer side of the door as is the ordinary construction. This key mechanism has an inner cylinder 87 controlled by the usual pass keys or guest keys 88 and also the master keys coacting with the usual pin tumblers 89. Carried by the inner end of this cylinder is a cam 90 which is secured to the cylinder by any suitable means, such as screws 91, so that it will rotate with this cylinder. There is also an auxiliary cylinder 92 rotatably mounted in the key barrel 86 and embracing the inner cylinder 87 at or adjacent its inner end. The rotation of this cylinder is controlled by an additional pin tumbler 93 which is controlled only by the

emergency key 94. The auxiliary cylinder 92 carries a lug 95 which is adapted to be engaged by shoulders 96 on the cam to limit the movements of the cam under action of 5 all keys except the emergency key. When mounted in the casing the cam 90 is adapted to engage the stumps or lugs 49 and 61 carried by the shutout lever 50 and the auxiliary controlling lever 60 respectively, de- 10 pending upon the location of these elements, as will presently be described.

The operation is as follows:

Fig. 2 shows the positions of the elements when the door is open. It will be noted that 15 in this position spring 39 has advanced or extended the auxiliary latch 38, and the head or plate 40 reacting on the inclined edge 41 of the blocking slide 32 has raised this slide withdrawing lug 36 from the path 20 of movement of the shoulder 37 on the latch bolt 23. This latch bolt is thus free to re-tract or move into the casing under the action of striking element 26 in coaction with the striking plate 17 when the door is 25 closed. It will also be noted that the master tumbler 46 is in its lowermost position with lug 49 carried by the shutout lever 50 resting in the notch 47. This tumbler, therefore, 30 holds the shutout lever against movement and retains it in the released position so that it cannot be moved to shutout position by the thumb knob 56 while the door is open.

Assuming now that the door is closed the 35 elements will be moved to the positions shown in Fig. 3. In this position the projecting end of latch bolt 23 has entered the opening 24 in the striking plate 17 and will retain the door in closed position. However, as the striking plate 17 has no opening for 40 the auxiliary latch 38, this latch will be retracted as shown. As this auxiliary latch is moved inwardly or retracted its head 40 co-acting with the inclined edge 57 on tumbler 46 has raised the tumbler to the position 45 shown, and will retain it in this position as long as the auxiliary latch 38 is retracted. The inward movement of this latch has also released the blocking slide 32 and it has been moved downwardly under the action of 50 spring 42 to bring lug 36 into alignment with the shoulder 37. It will thus hold the latch bolt 23 against retraction by an external means, such as a tool inserted between the door and the casing. The raising of the 55 tumbler 46 has also released shutout lever 50 as the notch 47 is moved away from the lug 49. The shutout lever 50 is, therefore, 60 free to be swung to the shutout position by the thumb knob 56, if desired. If the room is unoccupied the elements will be left in the 65 positions shown in Fig. 3, at which the lock is operable by all the keys, including the guest or pass keys, the master keys, and the emergency key. By reference to Fig. 6 it will be seen that when under the action of

any of the keys the cam 90 is turned to the right or clockwise, as viewed in this figure, it will engage the lug 61 on the auxiliary controlling lever 60 and by depressing this lever through this lug will, by pressure on finger 63 of master controlling lever 64, cause its finger 70 to engage head 31 and retract the bolt from the striking plate and unlock the door. 70

Assuming now that the room is occupied, 75 the occupant turns the thumb knob 56 to the position shown in Fig. 4 swinging the shutout lever 50 to bring lug 49 into notch 48 in the tumbler 46. When the elements are in 80 these positions all of the keys except the emergency key are blocked out or rendered inoperative. Should now the occupant wish to open the door all that is necessary is to turn the usual knob 76 which will both swing shutout lever 50 to the released position and 85 will withdraw the latch bolt 23 to allow the door to open. It thus releases the shutout mechanism and retracts the latch bolt, and the door may be opened without the necessity of manipulating the thumb knob 56, 90 and by manipulation of the main knob 76 only. This is accomplished as follows: Turning the knob 76 rotates cam 73 swinging the free end of hub lever 71 rearwardly or to the right, as viewed in Fig. 4. This will 95 act on finger 70 of lever 64 and swing finger 62 to the left. This finger acting on the end of lever 60 will depress this finger and cause the lug 61 reacting on the curved edge 97 of shutout lever 50 to swing this lever to the upright or released position shown in Fig. 2. At the same time finger 63 operates intermediate lever 78 lifting the blocking plate 32 to release the latch bolt 23 and finger 70 100 engages the head 31 and retracts bolt 23. 105 Thus turning of the knob 76 releases the shutout mechanism and retracts the bolt 23 rendering the lock panic proof. It has been found that when the shutout mechanism must be released by the thumb knob, in 110 cases where there is a fire the occupants may become so panic stricken as to forget to turn the thumb knob before operating the main latch knob, and are thus trapped in their rooms. It will be apparent that such a condition can never happen with this lock. 115

Furthermore, when the shutout mechanism is set in the shutout position, that is, with the elements in the positions shown in Fig. 4 the door can be unlocked from the outside only by the emergency key all of the other keys being rendered inoperative. It will be noted from an inspection of this figure and Fig. 7 that the lug 61 on the lever 60 has been raised by the curved edge 97 on lever 50, out of the path of movement of the cam operated by the keys, the path of movement of the free end of this cam being indicated by the dot and dash circle 98, and as this cam can be swung by means of the 120 125 130 135

- usual guest or pass keys and master keys only until shoulders 96 engage the stop 95, as shown in dotted lines Fig. 11, the lock cannot be operated with any of these keys.
- 5 The lock may, however, be operated by the emergency key 94. This key is of greater length than the other keys so as to control an additional pin tumbler 93 which controls the cylinder 92 carrying the stop lug 95.
- 10 Thus by means of the emergency key the cam 90 may be given a complete revolution, the cylinder 92 under these conditions turning with the cylinder 87. Thus, although the lug 61 is held by the shutout lever 50 out of the path of movement of the cam, still the lug 49 carried by the shutout lever is within the path of movement of this cam, as shown in Fig. 7, and turning of the cam by the emergency key will, by action of the cam on lug 49, swing the shutout lever to the unlocked or released position shown in Figs. 3 and 8. The cam 90 may then be swung back about a quarter turn past the lug 61, which will be lifted to allow the cam to pass, and by then turning the cam clockwise or to the right, as viewed in Fig. 8, it will engage the lug 61 and retract the latch bolt 23 allowing the door to be opened as described above.
- 15 If desired, the emergency key may be used to block out or render inoperative the guest and all other keys. To do this the emergency key may be used in the reverse operation from that just described, that is, by turning it in the opposite direction or counterclockwise, as viewed in Figs. 6 and 8, it will engage the left hand side of lug 49 and swing it from alignment with notch 47 to notch 48 or into the shutout position.
- 20 By then turning the cam back to the vertical position the emergency key may be withdrawn, and all the other keys will be blocked out or rendered inoperative. When the lever 60 is depressed through the action of the cam on lug 61, finger 63 on master control lever 64 will, through the medium of the intermediate lever 78, raise the blocking slide 32 and move lug 36 out of the path of movement of the shoulder 37. The same operation will take place when the latch is retracted by the hub lever 71, as shown in Fig. 5.
- 25 The shutout lever 50 is provided with a lug 81 which, when this lever is swung on its pivot, is moved to and from the path of movement of the inner end 82 of the telltale button 83. It is so arranged that when the door is locked by a manipulation of the thumb knob 56 the lug 81 will be in the path of movement of the telltale, as shown in Fig. 7, and so by preventing depression of this telltale will indicate that the room is occupied.
- 30 In the present showing the outer knob 99 is rigid, that is, has no movement, and so acts only as a push or pull in the act of closing or opening the door. Its square shank 100 rests in the squared opening 101 of holding block 102, which is held against rotation by lug 103 seating in a recess 104 in a projection 105 integral with the casing 18. If desired, however, this outer knob may be left operable to retract the latch bolt and the lock furnished with the usual stops in the face plate 20 on the edge of the door, which stops will control the operation of the outer knob in the usual manner. These stops are not shown as they are of the usual construction and form no part of our invention, and the addition of them to the drawing would tend to confuse the showing of the invention above described.
- 35 Having thus set forth the nature of our invention, what we claim is:
1. In a lock, a movable bolt, means for withdrawing said bolt from holding position, a second means for retracting said bolt, independent means for rendering the second means ineffective, and means operable by said first mentioned means to render said second mentioned means effective when said first mentioned means is operated to withdraw the bolt.
- 40 2. In a lock, a movable bolt, a knob on one side of the lock for controlling said bolt, means on the other side of the lock for operating the bolt, shutout means for rendering said bolt operating means ineffective, and means operable by the knob for releasing the shutout means.
- 45 3. In a lock, a movable bolt, a knob for controlling said bolt, a second means for operating the bolt, shutout mechanism for rendering the second means ineffective, and means operable by the knob for releasing said shutout mechanism when the knob is operated to move the bolt.
- 50 4. In a closure lock, a movable bolt, a rotatable knob on the inner side of said closure, means operated by the knob for withdrawing said bolt from holding position, means operable from the outer side of the closure for withdrawing the bolt, a thumb knob on the inner side of the closure, means operable by the thumb knob for shutting out the second mentioned bolt operating means, and means operated by the first mentioned knob for releasing the shutout means.
- 55 5. In a closure lock, a movable bolt, a rotatable knob on the inner side of said closure, means operable by said knob for controlling the bolt, means operable from the outer side of the closure for controlling the bolt, a rotatable thumb knob on the inner side of said closure, a shutout mechanism for the second bolt controlling means operable by said thumb knob, and means operable by the first mentioned knob to release the shutout mechanism when said knob is operated to move the bolt.

6. In a closure lock, a movable bolt, means on the inner side of the closure for withdrawing said bolt from holding position, key operated mechanism accessible from the outer side of said closure, shutout means for said key operated mechanism, independent means on the inner side of the closure for controlling the shutout means, and means operable by said first mentioned means to release the shutout means when said first mentioned means is operated to withdraw the bolt, said key operated mechanism being operable to move the bolt when said shutout means is released and inoperative to move the bolt when said shutout means is in shutout position. 70
7. In a closure lock, a movable bolt, a knob on the inner side of the closure for controlling said bolt, key operated means accessible from the outer side of the closure, shutout means for the key operated means, means on the inner side of the closure for controlling the shutout means, and means operable by the knob for releasing the locking means, said key operated means being operable to move the bolt when the shutout means is released and inoperative to move the bolt when the shutout means is in shutout position. 75
8. In a closure lock, a movable bolt, a knob on the inner side of the closure for controlling said bolt, a key operated means operable from the outer side of the closure, shutout means for the key operated means, means on the inner side of the closure for operating the shutout means, and means operable by the knob for releasing the shutout means, said key operated means being operable by different keys and operable by means of one of said keys to move the bolt when the shutout means is released and inoperative to move the bolt when the shutout means is in shutout position, said key operated means being operable by another key to release said shutout means. 80
9. In a closure lock, a movable bolt, means on the inner side of the closure for operating the bolt, key operated means accessible for operation from the outer side of the closure, shutout means for the key operated means, and means accessible from the inner side of the closure for controlling the shutout means, said key operated means being operable to move the bolt when the shutout means is released and inoperative to move the bolt when the shutout means is in shutout position. 85
10. In a closure lock, a movable bolt, means on the inner side of the closure for operating the bolt, key operated means accessible for operation from the outer side of the closure, shutout means for the key operated means, and means accessible from the inner side of the closure for controlling the shutout means, said key operated means
- being operable by different keys and operable by means of one of said keys to move the bolt when the shutout means is released and inoperative to move the bolt when the shutout means is in shutout position, said key operated means being operable by another key to release said shutout means. 90
11. In a closure lock, a movable bolt, means on the inner side of the closure for moving the bolt, a key operated cam accessible for operation from the outer side of the closure, shutout means for said cam, and means on the inner side of the closure for controlling said shutout means, said cam being operable a limited amount by a given key to move the bolt when the shutout means is released, and said cam being operable a greater amount by another key to release said shutout means. 95
12. In a closure lock, a movable bolt, means on the inner side of the closure for moving the bolt, a key operated cam accessible for operation from the outer side of the closure, shutout means for said cam, means on the inner side of the closure for controlling the shutout means, and means operable by the first mentioned means to release the shutout means, said cam being operable a limited amount by a given key to move the bolt when the shutout means is released and operable by another key a greater amount to release said shutout means. 100
13. In a closure lock, a movable bolt, means for operating said bolt, shutout means for said bolt operating means, a tumbler for controlling said shutout means, an auxiliary latch controlling the operation of said tumbler, and a striking plate for controlling the operation of said latch. 105
14. In a lock, a movable bolt, means on one side of the lock for operating said bolt, key controlled means on the other side of the lock for operating the bolt, shutout means for the key controlled means, a tumbler for controlling the shutout means, independent means for controlling the tumbler, and means controlled by the bolt operating means for releasing the shutout means. 110
15. In a door lock, a movable bolt, a knob on the inner side of said door, means operable by said knob for moving the bolt, key controlled means for operating the bolt, a tumbler, a shutout lever for the key controlled means controlled by said tumbler, a thumb knob on the inner side of the door for swinging said shutout lever to shutout position, and a lever operable by the first mentioned knob for moving the shutout lever from shutout position. 115
16. In a door lock, a movable bolt, a knob on the inner side of said door, means operable by said knob for moving the bolt, key controlled means for operating the bolt, a tumbler, a shutout lever for the key controlled means controlled by said tumbler, 120
- 130

a thumb knob on the inner side of the door for swinging said shutout lever to shutout position, an auxiliary latch for controlling the operation of the tumbler, a striking plate 5 for controlling the operation of said latch, and a lever operable by the first mentioned knob for moving the shutout lever from shutout position.

17. In a door lock, a movable bolt, a blocking slide movable to and from a position to block movement of said bolt, a knob on the inner side of said door, means operable by said knob for operating said slide and the bolt, key controlled means for operating the bolt, a tumbler, a shutout lever for the key controlled means controlled by said tumbler, a thumb knob on the inner side of the door for swinging the shutout lever to shutout position, an auxiliary latch for controlling the operation of said slide and tumbler, a striking plate for controlling the operation of said latch, and a lever operable by the first mentioned knob to move the shutout lever from shutout position.

18. In a door lock, a movable bolt, a knob on the inner side of the door for operating said bolt, a key operated cam accessible for operation on the outer side of the door, a shutout lever for said cam, a tumbler for controlling the shutout lever, an auxiliary lever controlled by the shutout lever for operating the bolt, and means on the inner side of the door for operating the shutout lever, said cam adapted to operate the auxiliary lever when the shutout lever is in released position and ineffective to operate the auxiliary lever when the shutout lever is in shutout position.

19. In combination, a door, a latch for said door, a knob on the inner side of the door for operating said latch, key controlled means for operating the latch, shutout means for the key controlled means, means operable from the inner side of the door for controlling the shutout means and means operable by the knob for releasing the shutout means.

20. In combination, a door, a latch for said door, a knob on the inner side of the door for controlling said latch, key controlled means for operating the latch, shutout means for the key controlled means, means independent of the knob for controlling said shutout means, and means operated by the knob for releasing the shutout means.

21. In combination, a door, a latch for said door, a knob on the inner side of the door for controlling the latch, key controlled means for operating the latch, shutout means for the key controlled means, a second knob on the inner side of the door for controlling the shutout means, and means for releasing the shutout means on

operation of the first knob to operate the latch.

22. In a door lock, a latch bolt, a knob on the inner side of the door for operating said bolt, a key operated cam accessible for operation from the outer side of the door, a stop controlled by another key for limiting the movements of said cam, means arranged to be engaged by said cam under movement limited by said stop for operating the bolt, and means operated by said cam under movement unlimited by said stop for moving said first mentioned means to and from the path of movement of said cam.

23. In a door lock, a latch bolt, a knob on the inner side of said door, a lever operated by said knob for retracting the bolt, a master control lever operable by said knob and also arranged to operate the bolt, an auxiliary controlling lever arranged to operate the master control lever also to be operated thereby under action of said knob, a key operated cam accessible for operation from the outer side of the door, said auxiliary controlling lever being provided with a shoulder arranged to be engaged by said cam for operating the bolt, means operable from the inner side of the door for moving said shoulder from the path of movement of said cam, and cooperating means carried by the master control lever and the auxiliary controlling lever to operate the latter lever to move the shoulder into the path of movement of the cam under action of the master control lever by the knob.

24. In a door lock, a latch bolt, a knob on the inner side of said door, a lever operated by said knob for retracting the bolt, a master control lever operable by said knob and also arranged to operate the bolt, an auxiliary controlling lever arranged to operate the master control lever and also to be operated thereby under action of said knob, a key operated cam accessible for operation from the outer side of the door, a lug carried by the auxiliary controlling lever adapted to be engaged by said cam to retract the bolt, a shutout lever for controlling the auxiliary controlling lever, means on the inner side of the door for controlling said shutout lever, a tumbler for controlling the operation of the shutout lever, and an auxiliary latch controlled by the position of the door for controlling the operation of said tumbler.

25. In a door lock, a latch bolt, a knob on the inner side of said door, a lever operated by said knob for retracting the bolt, a master control lever operable by said knob and also arranged to operate the bolt, an auxiliary controlling lever arranged to operate the master control lever also to be operated thereby under action of said knob, a movable cam, key controlled means for

- operating said cam, a stop for limiting movements of the cam under action of said key controlled means, a second key controlled means for moving said stop to allow further movement of the cam, a lug carried by the auxiliary controlling lever and adapted to be engaged by the cam under movement of the first key controlled means, means operable by the cam under movement by the second key controlled means for moving the lug to and from the path of movement of the cam under action of the first key controlled means, and cooperating means on the master control lever and the auxiliary controlling lever to operate the latter lever to move the lug into the first mentioned path of movement of the cam under action of the master control lever by the knob.
26. In a door lock, a latch bolt, a knob on the inner side of said door, a lever operated by said knob for retracting the bolt, a master control lever operable by said knob and also arranged to operate the bolt, an auxiliary controlling lever arranged to operate the master control lever and also to be operated thereby under action of said knob, a movable cam, key controlled means for operating said cam, a second key controlled means for limiting the movement of the cam under action of the first key controlled means, a lug carried by the auxiliary controlling lever and adapted to be engaged by the cam to operate the bolt, a shutout lever arranged to move the said lug from the path of movement of the cam, a lug carried by the shutout lever, and means on the inner side of the door for operating the shutout lever, said lug on the shutout lever arranged to be engaged by the cam to operate said lever under the second key controlled means, and said lug on the auxiliary controlling lever arranged to swing the shutout lever to releasing position under operation of said knob.
27. In a door lock, a latch bolt provided with a shoulder, a knob on the inner side of said door, a lever operated by said knob, a master control lever provided with a plurality of fingers one of which is between the first mentioned lever and said shoulder, 50 an auxiliary controlling lever extending between a pair of said fingers and provided with a shoulder, a key controlled cam arranged to coact with said shoulder to operate the bolt, a shutout lever arranged to move said shoulder from the path of movement of said cam, and means on the inner side of the door for controlling the position of the shutout lever.
28. In a door lock, a latch bolt, a knob 60 on the inner side of said door, a lever operated by said knob for retracting the bolt, a master control lever operable by said knob and also arranged to operate the bolt, an auxiliary controlling lever arranged to operate the master control lever and also to be operated thereby under action of said knob, a key operated cam accessible for operation from the outer side of the door, said auxiliary controlling lever being provided with a shoulder arranged to be engaged by said cam for operating the bolt, means operable from the inner side of the door for moving said shoulder from the path of movement of the cam, a blocking slide 70 for controlling the operation of said bolt and normally in a position to prevent retraction of the bolt when the door is closed, and an intermediate lever between the master control lever and the slide for moving the slide from holding position upon operation of the master control lever.
29. In a lock a movable bolt, means on one side of the lock for operating said bolt, key controlled means on the other side of 85 the lock for operating said bolt, shutout means for the key controlled means, a tumbler for controlling the shutout means, means controlled by the first bolt operating means for releasing the shutout means, an auxiliary latch for controlling the operation of said tumbler, and a striking plate for controlling the operation of said latch.

In testimony whereof we affix our signatures.

ALEXANDER K. MORTON.
JOHN A. HALLORAN.
